(57) **CLAIM**

The ornamental design for a holder for flexible flat cable, as shown and described.

DESCRIPTION

FIG. 1 is a perspective view of a first embodiment of a holder for a flexible flat cable, as viewed from top, front and right side, showing our new design;

FIG. 2 is a perspective view thereof, as viewed from bottom, rear and left side;

FIG. 3 is a top plan view thereof;

FIG. 4 is a front elevation view thereof, a rear elevation view thereof being same image;

FIG. 5 is a right side view thereof, a left side view thereof being same image;

FIG. 6 is a bottom plan view thereof;

FIG. 7 is a perspective view of a second embodiment of the holder for a flexible flat cable, as viewed from top, front and right side;

FIG. 8 is a perspective view of the embodiment of FIG. 7, as viewed from bottom, rear and left side;

FIG. 9 is a top plan view of the embodiment of FIG. 7;

FIG. 10 is a front elevation view of the embodiment of FIG. 7, a rear elevation view thereof being same image;

FIG. 11 is a bottom plan view of the embodiment of FIG. 7;

FIG. 12 is a right side view of the embodiment of FIG. 7, a left side view thereof being same image;

FIG. 13 is a perspective view of a third embodiment of the holder for a flexible flat cable, as viewed from top, front and right side;

FIG. 14 is a perspective view of the third embodiment, as viewed from bottom, rear and left side;

FIG. 15 is a top plan view of the embodiment of FIG. 13;

FIG. 16 is a front elevation view of the embodiment of FIG. 13, a rear elevation view thereof being same image;

FIG. 17 is a bottom plan view of the embodiment of FIG. 13; and,

FIG. 18 is a right side view of the embodiment of FIG. 13, a left side view thereof being same image.
